PULSE MODULATING SYSTEM

Gaston Potier, Versailles, France, assignor to
 Societe francaise Sadir-Carpentier, Paris,
 France, a corporation of France

Application July 13, 1946, Serial No. 683,299
 In France July 31, 1945

3 Claims. (Cl. 332—15)

1

The present invention relates to electric signalling by means of width modulated pulses and more particularly to certain improved means for generating modulated pulses the length of which is a linear function of the instantaneous amplitude of a modulating signal.

Fig. 1 is a diagrammatic showing of width modulated saw tooth pulses;

Fig. 2 is another diagrammatic showing of width modulated saw tooth pulses;

Fig. 3 shows a circuit diagram illustrating an embodiment of the invention;

Fig. 4 shows the pulse diagram corresponding to said circuit embodiment;

Fig. 5 shows a circuit diagram illustrating another embodiment of this invention;

Figs. 6, 7 and 8 show the pulse diagrams corresponding to embodiment shown in Fig. 5;

Fig. 9 shows a conventional diagram of a modulation system for pulse multiplex transmission, using time division;

Fig. 10 shows the pulse distribution in a system such as shown in Fig. 9;

Fig. 11 shows a general diagram of a modulation system for multiplex transmission, according to the general process of the present invention; and

Figs. 12 and 13 show two examples of application of the invention to multiplex transmission systems, employing the circuits of Figs. 3 and 5 respectively.

Heretofore, a generally utilised process for generating width modulated pulses consisted as diagrammatically shown in Fig. 1 of the annexed drawings, of superimposing on the modulating signal (curve 1), of saw-tooth shaped signals 2, 3, of prerequisite recurrence frequency, constant amplitude and slope. A suitable device, such as a clipper stage associated with a gating circuit, converts that portion of the saw-tooth which is above a predetermined level indicated by line 4 into a rectangular pulse the width of which equals that of the saw-tooth at said level. This width is a function of the instantaneous amplitude of curve 1 as the saw-teeth are of invariant shape, hence the required result is obtained.

In the application of such a process, it is very difficult to obtain a substantially linear relation between the length (or duration) of the pulses and the instantaneous amplitude of signal 1, which results in a noticeably high degree of distortion; furthermore, the following disadvantage occurs: in the case of an overmodulation, i. e. when the amplitude of the modulating signal exceeds the level of line 4, the device delivers a pulse

2

of a width equal to AB as shown in Fig. 1 whether or not a saw tooth such as 5 does exist. This width AB may be of much greater value than the maximum width of the concerned saw-tooth.

5 This may give an idea of the ensuing trouble.

According to certain features of the invention, such trouble is eradicated by providing first an amplitude modulation of the pulses and then converting said amplitude-modulated pulses into corresponding length-modulated pulses. Otherwise the pulses of the recurrence frequency equal to that of the final pulses to be generated are first derived from the modulating signal 1 (Fig. 2), such pulses being of a fixed width equal to the maximum width admitted for such final pulses, and having an amplitude equal or linearly related to the instantaneous value of said signal 1. To the pulses 6, illustrated as hatched areas, are then added saw-tooth pulses 7 as in the above described generating process, the bottom width of which equals that of pulses 6, the following operations being such as summarized with respect to Fig. 1.

The way in which pulses such as 6 are obtained 25 from signal 1 is well-known in itself. One may see that, in such a case as provided by the invention, any trouble from an overmodulation is avoided as, in all cases, the width of the finally generated pulse cannot exceed that of pulses 6, at whatever level the clipping may occur.

Other features of the invention relate to certain particular means for generating pulses 6 and 7 as well as for providing circuits therefor which comprise only a small number of vacuum tubes, thus enabling a great manufacturing economy of the apparatus embodying such features.

Other features of the invention relate also to certain particular manners of applying such process and means as provided above, to multiplex transmissions in order to obtain an important reduction of tubes and associated equipment.

Referring to Fig. 3, in the circuit shown, the pentode tube 8 is used for generating amplitude-modulated pulses; for this purpose, its control grid receives, from generator 9, through a resistance-capacitance connection, rectangular positive pulses of constant amplitude and width and of the required recurrence frequency. A modulating signal is supplied from generator 10 to the suppressor grid of tube 8, a suppressor bias being provided by D. C. source 11 such that the operating point of the tube 8 is placed at the mid-point of the linear portion of said suppressor characteristic. Thus, in the plate-circuit of tube 8 negative amplitude-modulated pulses are generated

and said pulses are applied through a network comprising resistance 12 and capacitance 13 to the terminals of a grounded resistor 14. The generator 9 is connected to the control grid of said tube 8 through a resistance 20-capacitance 21 network. The resistance 20 is of high value and tube 8 is blocked between the pulses delivered by generator 9, according to the well-known rectifying process occurring in the tube grid-cathode space, which ensures a definite and accurate conversion of signal 1 into pulses 6 (Fig. 2).

Across the terminals of resistor 14, a condenser 15 and a diode (or other rectifying element) 16, the cathode of which is grounded, are series-connected. A constant-current generator 17, of any suitable kind has its positive pole connected to the plate of said diode. The purpose of such a combination 14-15-16-17 is to generate saw-tooth waves and superimpose them upon the afore-mentioned amplitude-modulated pulses. Its operation will be explained in relation to the curves shown in Fig. 4 in which voltages are plotted against time for three different heights of the pulse delivered by tube 8.

With no negative pulses supplied by the tube 8, the current of generator 17 passes through diode 16, the internal resistance of which may be considered as negligible. Curves *a* indicate the voltages with respect to the ground across resistor 14, which are developed by the transmitted pulses. As soon as a negative pulse appears, the voltage at points C and D, Fig. 3, becomes negative, the time constant of the network 15-16 being negligible, as a result, diode 16 is blocked. Hence the constant current output of generator 17 only flows through the 14-15 network, which creates a constant voltage across the terminals of resistor 14 and a voltage linearly related to time across the terminals of condenser 15 until the voltage at point D changes again to that of the ground. The diode 16 which then becomes conductive, prevents said voltage from taking any positive value. All elements are so dimensioned that the maximum duration of the charge of condenser 15 is at most equal to the duration of any pulse 6 of Fig. 2. Curves *b* indicate voltage across point D and ground, in the shape of saw-teeth which begin at points E₁-E₂-E₃, determined by the amplitude of the corresponding pulse *a*. The current generated by 17 being of constant value, points F₁-F₂-F₃ where a saw-tooth meets the zero voltage axis is a function of the amplitude of the corresponding pulse.

In other words, the spacing G₁F₁ (or G₂F₂ or G₃F₃) is linearly related to the amplitude of the corresponding *a* pulse, which is obviously the wanted result. When pulse *a* ceases, the voltage at point C is suddenly changed to the ground voltage, that at point D is suddenly raised, but this condition does not last, condenser 15 quickly discharging through diode 16. Thence, a positive peak P₁ (or P₂ or P₃) appears on curves *b*, but this departure does not introduce any trouble since it is suppressed by the unit 19 following tube 18, (for which a triode is shown but a pentode is of more advantageous use). Upon the control grid of tube 18 is applied the voltage between point D and ground. The tube 18 is permanently operated except for the periods in which the saw-tooth negative pulses are received. The circuit constants are such that, even for the smallest amplitudes as G₃E₃ of the sawtooth pulses, the plate current of 18 is partially suppressed, thus giving curves *c* of Fig. 4 which show the voltages appearing across the plate load resistance of tube 18.

These curves are then converted into rectangular pulses *d* the width of which is a time function of the signal amplitude from 10, such a conversion taking place in the unit 19 in any well known manner. It shall be noted that the saw-teeth *b* are obtained from the beginning of the charge of condenser 15, so as to use the desired linearity of charge characteristic, and that the discharge characteristic, which always presents a curvature to some degree, is not used as in other usual modulation systems.

From an illustrative point of view, a circuit designed as above has given modulated pulses of a maximum width of 1.5 μ s of a mean width of 1 μ and of a periodicity of recurrence equal to 3.2 μ s, the linear distortion degree being about 2%, without special care involved.

It is also to be noted that in the described system, the fronts of the pulses remain fixed (i. e. coincident with the fronts of the signals supplied by generator 9) the rear faces of said pulses moving in accordance with the modulating signal, which may be taken advantage of, in some cases.

An alternative, which may be useful for some applications, consists of the omission of diode 16, the function of which may be accomplished by the grid-cathode space of tube 18, when the internal resistance of said space is low with respect to the value of resistor 14.

30 The circuit shown in Fig. 5 makes use of the charge, under constant current, of a condenser 28, until it reaches a value fixed by the instantaneous voltage of the modulating signal, after which the charge current is by-passed through a 35 secondary circuit comprising a resistance 34 across the terminals of which the width-modulated pulse may be picked up.

In Fig. 5, a generator 9 generates rectangular pulses at an uniform recurrence frequency (that 40 which is wanted for the final output pulses) and of suitable fixed amplitude and width. These pulses, of positive sense, are applied to the control grids of two tubes 22 and 23 (pentode tubes, for example, the screen and suppressor grids of tube

45 22 having been omitted for the sake of clearness in the drawing) by means of resistance-capacitance networks 24-25 and 26-27. These tubes are unblocked during the pulses and blocked in the intervals between the pulses due to the charges 50 picked-up by condensers 24 and 26. The plate circuit of tube 22 comprises a condenser 28 across which is connected a pentode or triode tube 29. The plate circuit of tube 29 comprises a resistor 30 the lower end of which is connected to the grid 55 of tube 29. The screen-grid of tube 23 is supplied, in a well known manner, by a network constituted by resistors 31-32 and condenser 33. The plate circuit of tube 29 also comprises a resistor 34 of a relatively low value, for a purpose which will 60 be further indicated.

The modulation voltage from generator 35 is fed to the suppressor grid of tube 23 by means of a network resistance 37 and capacitance 36. A suitable bias is supplied to this grid from battery 65 38. This tube 23 operates as described for tube 8, in Fig. 3 and thus delivers at the terminals of its load resistance 30, amplitude-modulated pulses of the same width as those delivered by generator 9. An output pulse of constant amplitude from 70 generator 9 is shown at *a*, Fig. 6, and at *b* is shown the pulse which synchronously appears across resistor 30, but is of varying amplitude.

As soon as tube 22 is unblocked, condenser 28 begins to charge and this charge lasts until tube 75 29 is unblocked, which as may be easily seen,

occurs when the voltage across capacitor 28 equals the voltage across resistor 36 plus the voltage of cut-off, which is practically negligible.

From this moment, the plate current of tube 22 flows through tube 29; resistance 34 being of low magnitude, introduces only a negligible voltage drop; hence condenser 28 retains its charge as long as the positive pulse applied on tube 22 lasts. As soon as said pulse ends, tubes 22 and 23 are blocked. Condenser 28 discharges through resistor 34 and tube 29 and the voltage across this condenser 28 varies as shown in curve c, Figs. 6, 7 and 8. The voltage across resistor 34 is such as shown in curve d, Figs. 6, 7 and 8. It is clear, from the above, that the equal widths of the flat portions of curves c and d are linear functions of the amplitudes of pulses b, Figs. 6, 7 and 8, since the charge of condenser 28 is effected with a constant current condition through pentode tube 22.

The resulting width-modulated pulses are collected across resistance 34. It will be noted that, in the circuit shown in Fig. 5, the higher the modulation voltage, the smaller the width of the generated pulse. This indicates that the linear relation between the modulation voltage and the pulse width is a decreasing one. Moreover, it is now the rear edge of the pulse and not the front edge, that is fixed, and this rear edge coincides with the rear edge of the pulse delivered by generator 9.

It shall be noted that, in addition to generator 9, Fig. 3, the circuit utilises three tubes only, which leads to an economical design.

The invention also provides for the application of such process and means as here above described to multiplex transmissions with a view of greatly reducing the required number of tubes and associated elements.

The process generally utilised for obtaining width-modulated pulses is shown in Fig. 9. A pilot pulse generator 41 feeds a delay line 42 comprising a number of output terminals n equal to the number of channels in the concerned system. At these terminals, appear pulses, regularly shifted in time which are brought to n modulators 43 controlled by the modulating voltages from the various channels. Width-modulated pulses are thus collected at the output of said modulators and fed to a mixer circuit 44 also supplied through a connection 45 with a pilot pulse (used, at the far end, for the purpose of selecting the various channels). The mixer 44 comprises, for instance, an impedance common to the plate output circuits of the last stage tubes of circuits 41 and 43.

Fig. 10 shows at a the pulses supplied by generator 41 and pulses b and c represent those fed by modulator 43, to the mixer 44 and pulses d represent the complete train at the output of mixer 44.

The modulators 43 may consist of a minimum of three tubes although generally four tubes are employed not considering the tubes in the generator 51 associated with each of the units 43.

The number of tubes N may be appreciably decreased if, according to some features of the present invention, the operation process is made as follows:

- (1) Amplitude-modulated pulses are generated for every channel;
- (2) Said pulses are mixed;
- (3) Those mixed amplitude-modulated pulses are converted by a single element into width-modulated pulses;

(4) Width-modulated pulses are mixed with the pilot pulse train.

Such an arrangement is shown in Fig. 11, in which 41 is a pulse generator, 42 is a delay line, 46 are modulators delivering amplitude-modulated pulses, 47 is a mixer for pulses fed from modulators 46, 48 is a pulse converter from amplitude-modulated into width-modulated pulses and 49 is a second mixer adding pilot pulses fed by conductor 45 to said width-modulated pulses. As the mixers do not require any tube and a single tube per channel is only necessary for generating amplitude-modulated pulses, the total number of tubes is then:

$$N' = n + K$$

in which K is the number of tubes required for the converter circuit. As $K=3$ or 4 and n from 6 to 20 or higher, it is seen that N' is much less than N . Hence a substantial economy of tubes and associated elements, and a decrease in capacity of supply sources is effected by this invention.

Fig. 12 is a schematic diagram of a multiplex circuit in which the modulators 46, mixer 47 and pulse converter 48 are designed according to the embodiment of Fig. 3, the parts of said Fig. 3, unnecessary for an understanding of said circuit, being omitted. The pulse generator 41 and the delay line 42 are connected as in Fig. 11. The generation of amplitude-modulated pulses is effected by means of a pentode tube 50 (tube 3 of Fig. 3) the suppressor grid of which is supplied by the output signal of a generator 51, of the channel concerned. Tube 50 taken along with generator 51 and associated elements constitutes a modulator indicated as 51. There are n such modulators provided in the system. The plate circuits of the n tubes 50 are connected by a resistance-capacitance network to a resistance 52. These plate circuits may comprise a common resistance which is connected to the resistor 52 by a single coupling condenser. Across the resistance 52 are connected a condenser 53 and a diode or other rectifier 54 supplied with the output of a constant current generator 55. Then a clipping circuit 56 suppresses the top of all signals to a predetermined level and a second mixer adds the pilot signal to the pulses thus shaped. All elements 52-56 and 59 constitute a single apparatus 58 common for all channels, the operation of which may be easily understood from the preceding description.

Fig. 13 shows an embodiment making use of the circuit of Fig. 5. Here also superfluous details are not shown; only the generator 41, delay line 42, modulator tube 50 and generator 51, as described above.

Moreover, the terminals of the line 42 are connected through coupling condensers 59 and separating resistances 67, of high value with respect to the characteristic impedance of the line 42, to a common conductor 60 connected to the grid of tube 61 (tube 22 in Fig. 5). A leak resistance 66 determines the potential of the grid of the tube 61 as well as the amplitude ratios of the signal applied to this grid and the potential of the various signals at the terminals of the delay line. The plate circuits of tubes 50 have a common load resistance 62 (30 in Fig. 5) controlling the grid potential of tube 63 (29 in Fig. 5) with a plate resistor 64 across which width-modulated pulses are delivered, which are amplitude-limited at 56 and mixed with pilot pulses in 49. Here again, the elements 50-51 constitutes a channel modulator 51 (one for each channel) and the elements

61 to 64 a single unit 65 common to all channels.

Having now described and ascertained my invention, I declare that what I claim is:

1. A process for generating width-modulated electrical pulses, by which a substantially linear relation is ensured between the width of each pulse and the corresponding instantaneous amplitude of the modulating signal, comprising the steps of generating amplitude modulated pulses, by generating from a modulating signal pulses of a recurrence frequency equal to that of the final width-modulated pulses wanted, of fixed width equal to the maximum width required for said final pulses and of varying amplitude equal or proportional to the instantaneous amplitude of the modulating signal, the further step of converting said amplitude modulated pulses into width modulated pulses by adding to said amplitude modulated pulses, saw toothed pulses, the height of which is at least equal to the maximum amplitude variation of said modulating signal and the width of which is equal at the base to that of the fixed width of said amplitude-modulated pulses, the further step of clipping said combined pulses at a constant inferior level, suitably determined about the maximum amplitude of said constant-width pulses.

2. A combination for the generation of width-modulated electrical pulses comprising, means for generating substantially rectangular pulses of substantially constant amplitude, width and recurrence frequency, means for generating a modulating signal, a pentode tube, means for applying said pulses and modulating signal to electrodes of said pentode tube, means for biasing said pentode to cause it to deliver pulses of constant width and recurrence frequency having amplitudes that are in linear relation to the corresponding linear amplitudes of said modulating signal, means for generating from a constant current source, and under the control of said amplitude-modulated pulses, saw-toothed pulses of the same width as said amplitude-modulated pulses of the same recurrence frequency and of a height at least equal to the maximum variation of amplitude of said amplitude-modulated pulses, means for adding said amplitude-modulated pulses and

said saw-toothed pulses and means for applying the resulting pulses to a gating circuit which suppresses the portions of said combined pulses lower than a predetermined level substantially adjusted to the maximum amplitude of said amplitude-modulated pulses, in order to obtain pulses of a varying width in a substantially linear relation to the amplitude of said amplitude-modulated pulses.

3. The combination for the generation of width modulated electrical pulses comprising, means for generating substantially rectangular pulses of constant amplitude, width and recurrence frequency, a vacuum tube, means for generating a modulating signal, means for applying said pulses and modulating signal to electrodes of said vacuum tube, means for biasing said vacuum tube to cause it to deliver pulses of constant width and recurrence frequency, the amplitude of which are in linear relation to the corresponding linear amplitudes of said modulating signal, means for generating saw-toothed pulses from said rectangular constant amplitude pulses, said saw-toothed pulses being of the same width and recurrence frequency as said amplitude-modulated pulses and of a height at least equal to the maximum variation of amplitude of said amplitude-modulated pulses, means for adding said amplitude modulated pulses and said saw-toothed pulses and means for applying the resulting pulses to a gating circuit which suppresses the portions of said combined pulses lower than a predetermined level substantially adjusted to the maximum amplitude of said amplitude-modulated pulses, in order to obtain pulses of a varying width in a substantially linear relation to the amplitude of said amplitude-modulated pulses.

GASTON POTIER.
